UNITED STATES PATENT OFFICE.

RUBY ROOT, OF SAN DIEGO, CALIFORNIA.

BUTTON-FASTENER.

1,317,759.

Specification of Letters Patent. Patented July 27, 1920.

Application filed April 28, 1919. Serial No. 293,316.

To all whom it may concern:

Be it known that I, RUBY Root, a citizen of the United States, residing at San Diego, in the county of San Diego and State of California, have invented a certain new and useful Button-Fastener, of which the following is a specification.

My invention relates to a button fastener for securing buttons to wearing apparel, 10 more particularly buttons with an extended lug with a hole therein and the objects of my invention are: first, to provide a fastener for securing buttons to wearing apparel which will not lose out or tear the cloth; 15 second, to provide a fastener of this class which may be used in connection with any kind or class of wearing apparel and with any kind or class of button with a projecting portion; third, to provide a fastener of this 20 class which will not loosen and which will not catch on articles that contact therewith and fourth, to provide a fastener of this class which is very simple and economical of construction, durable, easy to connect 25 with the button and which will not readily deteriorate or get out of order.

With these and other objects in view as will appear hereinafter, my invention consists of certain novel features of construction, combination and arrangement of parts 30 and portions as will be hereinafter described in detail and particularly set forth in the appended claims, reference being had to the accompanying drawings and to the characters of reference thereon which form a 35 part of this application, in which:

Figure 1 is a perspective view of a coat with the buttons in position thereon; Fig. 2 is a sectional view of the button structure alone; Fig. 3 is a side elevational view of the button and fastener shown in position on a garment lapel, which garment lapel is shown in section to facilitate the illustration; Fig. 4 is an inner elevational view 45 of the fastener alone and Fig. 5 is an edge view thereof.

Similar characters of reference refer to similar parts and portions throughout the several views of the drawings.

50 The button member 1, disk member 2, spring member 3 and latch member 4 constitute the principal parts and portions of my button fastener.

The button 1 is of the conventional form 55 of button with an extended lug 1^a adapted to extend into a small hole in the garment

and provided with hole 1^b therethrough. The fastener portion consists of a disk 2 of suitable size say approximately one-fourth to one-third the size of the button 60 and may be either straight or concavo-convex in form. Secured to the inner side of this member 2 is a spring member 3 which is preferably provided with a coil 3^a and secured near the side. It is provided with 65 an offset portion 3^b adapted for the hole 1^b in the lug 1^a adapted to prevent the movement of the spring 3 relative to said lug 1^a when in position therein. The extended end of the spring 3 engages a latch 4 which 70 is preferably a double latch as shown best in Fig. 5 and of sufficient width so that the end of the spring is covered to prevent its engagement with articles with which it may come in contact and the latch member 4 75 being so formed for interlocking with the end of the spring member 3 so that it will not be disengaged except by forced pressure for such purpose.

It is obvious that with this construction 80 there is provided a means for securing buttons to garments of different class which will not lose off and which will not pull through the hole through which a portion of the button protrudes, and in which the relation of the fastener with the button is always maintained so that the lug of the button is intermediate the ends of the spring member 3 at all times, that the device as a 85 whole is very simple and economical of construction, durable and will not loosen, lose off or deteriorate.

Having thus described my invention what I claim as new and desire to secure by Letters Patent, is:

1. In a device of the class described, the combination with a conventional button with an extended lug, of a disk member, a spring member provided with an offset 90 therein adapted to engage the lug of the button and rigidly secured to one side of said disk member and an interlocking latch secured to the opposite side of said disk member for receiving the end of said spring member.

2. In a device of the class described, the combination with a conventional button with a lug with a hole therein, of a spring pin adapted to fit in said hole, a disk to which one end of said spring pin is rigidly secured at one side thereof, and a latch rigidly secured to the opposite side of said 110

disk adapted to receive the other end of said spring pin.

3. In a device of the class described, the combination with a conventional button with a lug with a hole therein, of a spring member provided with an offset adapted to fit in said hole, a disk to which one end of said spring member is rigidly secured at one side thereof, a latch rigidly secured to

the opposite side of said disk adapted to receive the other end of said spring member comprising a double folded plate member whereby the end of said spring member is interlocked therein. 10

In testimony whereof, I have hereunto set my hand at San Diego California this 18 day of April 1919. 15

RUBY ROOT.
